TREATMENT OF WELLS

Harvey T. Kennedy, Forest Hills, and Blaine B. Wescott, Oakmont, Pa., assignors to Gulf Research & Development Company, a corporation of Delaware

Application October 3, 1935, Serial No. 43,440

6 Claims. (Cl. 166—21)

This invention relates to treatment of wells; and it comprises a method of selectively sealing or solidifying water bearing strata in wells which penetrate such strata and which also penetrate 5 underlying strata which it is desired not to treat; the method comprising the steps of introducing into the well a body of a suspension forming a gel-like mass up to a level adjacent but below the level to be sealed or solidified, and then introducing sealing or solidifying agents into the well and surrounding formations, the agents being prevented by a gel-like mass from penetration 10 into the strata which it is not desired to treat; all as more fully hereinafter set forth and as 15 claimed.

Oil wells often pass through water bearing formations: shifting sands or pervious rock bearing flowing water or brines. It is usually essential to restrain or shut off these formations. 20 flow of water to a well either during drilling or production is undesirable for many reasons.

In the past, when a water bearing formation was encountered during drilling, the usual procedure was to drill beyond the water-producing 25 stratum, run in casing, cement or pack it off and proceed with a drill of smaller diameter. This procedure required that an additional inner string or smaller diameter casing be employed each time the diameter of the bore was diminished, making it an extremely expensive operation. Recently, however, there have been 30 developed chemical methods of sealing or plugging such water-bearing formations by impregnation. These involve injecting one or more relatively 35 mobile solutions or suspensions of agents which give an insoluble precipitate, clot or coagulum of some sort in the water stratum. Such methods obviate the necessity for running a casing prematurely.

40 Chemical shut-off methods have also been employed for shutting off water in the uncased portion of completed wells.

One disadvantage of such procedures is that when the strata to be sealed are located not at 45 the bottom of the well but some distance above, as is often the case, excessive quantities of solutions have been required; and the plugging solution standing in the well below the level under treatment does no good and may obstruct underlying oil bearing strata. Waste occurs. This is 50 true both in wells being drilled and in completed wells.

The present invention presents an improvement upon such procedures. According to the 55 invention the well is first partly filled with an

inert suspension adapted to form a gel on standing in the well. Or the gel is formed in the well by inserting dry gel-forming materials and then adding water. Enough gel is provided to shut off the lower portions of the well up to the level 5 under treatment or at least enough to close off underlying strata such as oil strata which it is desired not to plug permanently. Then there is injected a suitable sealing agent. The gel forms in effect a solid table or column which 10 effectively prevents waste of any sealing agent by penetration into the well below the desired level. When there are oil bearing strata below the water layers, as is often the case, the gel body temporarily closes off such strata and prevents any plugging action thereon. After the sealing operation is finished, the gel body can 15 be withdrawn, leaving the oil strata exposed.

The most useful gel for our purpose, on the 20 whole, is one made from bentonite and water. A fluid suspension can be made from bentonite which is readily pumped and piped but which sets on standing to a firm gel. Such a gel has 25 thixotropic properties; while undisturbed it has almost a solid or rigid character, but on agitation as by pumping or bailing it turns freely liquid. A suspension of 3 to 5 parts commercial bentonite in 100 parts water is satisfactory. Organic gel forming materials can be used, such as 30 aqueous starch gel, if desired.

The sealing agent for the water bearing layers 35 can be of one of several different types. A particularly good sealing agent is silicon tetrachlorid, either in its pure (liquid) state or in oil solution. Such solution can be readily injected 40 far into porous formations bearing water. Gradual interaction with the water occurs, with the development of a bulky precipitate of hydrated silica. Other good sealing agents are water-soluble soaps of a type adapted to give a precipi- 45 tate in local waters; e. g. rosin size.

In an example of one specific embodiment of 50 the invention, an oil well of depth 5000 feet, of which the last 300 feet is uncased, has an oil producing stratum near the bottom and a water bearing stratum 200 feet above the bottom at the 55 4800 foot level. It is required to shut off the water stratum. According to the invention there is made up a batch of bentonite suspension sufficient to fill the well up to just below the level of the water stratum. The suspension is pumped in and allowed to assume a solid state. Then there is injected far into the water formation, by pumping under high pressure, a solution of 15 parts silicon tetrachlorid in 100 parts oil (by 55

weight). In the presence of water, the silicon tetrachlorid is decomposed with the formation of a bulky precipitate of hydrated silica, which effectively plugs the pores of the water formation. 5 Then the bentonite body is removed by bailing or pumping, leaving the oil stratum exposed and free to produce.

Sometimes the (metal) casing of an oil well becomes perforated through corrosion and water 10 enters the casing through the perforations. These perforations may occur a long distance from the bottom of the well. In such instances, the interior of the casing is filled with gel body to a point adjacent and below the point of water intrusion. The sealing agent is then introduced 15 into the interior of the casing and forced out of the perforations and into the water-bearing stratum by application of pressure at the casing head.

20 When the well to be treated is uncased in the region to be treated, the sealing agent is merely introduced above the gel body.

Typical applications of the method of the invention are illustrated in the accompanying diagrammatic drawing, in which:

Fig. 1 shows the application of the invention in sealing off a water stratum in the uncased portion of a completed well, the uncased portion having a water producing stratum overlying an oil 30 producing stratum and

Fig. 2 shows the application of the invention in sealing off a water stratum which is adjacent to the cased portion of an oil well, the casing having been perforated by corrosion to such an extent as to permit intrusion of water.

Referring to Fig. 1, reference character 1 indicates the upper portion of the bore of an oil well having a casing 2 resting on a rock-shoulder 3 of the bore 1. Adjacent the bore 1 are firm 40 rock strata 4 and a water bearing stratum 5 interposed therebetween. In accordance with the known practice, casing 2 is cemented as at 6 to prevent intrusion of water from stratum 5. Beneath the upper portion 1 of the bore is an 45 uncased portion 7 penetrating, in downward order, an unfirm or shifting stratum 8, a water bearing stratum 9, a firm stratum 10, and an oil producing stratum 11. When the well was first completed, stratum 9 produced oil; hence the well 50 was not cased below the point shown. However, owing to the formation in stratum 9 having greater permeability than that in stratum 11, the oil originally present in stratum 9 has been exhausted and water is now entering the well 55 bore through the latter stratum. Stratum 11 is still producing oil, and it is desired to shut off the flow of water from stratum 9.

In accordance with the present invention, the bore 7 is filled up to a point below and adjacent 60 stratum 9 with a body of gel 12. There is then introduced above the gel body 12 a charge of plugging agent 13, the plugging agent being accurately positioned and held at the desired location by virtue of being supported on the gel body. 65 Pressure is applied to the charge 13 from above, as by a column of oil, to force the plugging agent into the water bearing stratum 9. When the plugging action is complete, the gel charge 12 is pumped or bailed out, leaving the oil stratum 70 11 free to produce, while the water stratum is left effectively plugged.

Referring to Fig. 2, the upper portion 1 of an old oil well is shown having a casing section 2 resting on a shoulder 3. Adjacent the portion 1 75 are shown rock strata 4 and water-bearing stra-

tum 5 interposed therebetween. Casing 2 has been cemented as at 6 to prevent intrusion of water and is still sound and impermeable. Below upper portion 1 of the well bore is shown an intermediate portion 14 of smaller diameter. 5 Bore 14 passes through a second water bearing stratum 15 and is cased by an inner string of casing 16 resting on a shoulder 17 and cemented as at 18. Beneath the shoulder 17 the bore is of even smaller diameter and is uncased to permit 10 ingress of oil from formation 11. As illustrated, the inner string of casing 16 has become perforated by corrosion at the level of water stratum 15 and water is entering the casing through the 15 perforations 19.

In accordance with the present invention, enough gel body 12 is introduced into the well to entirely fill bore 7 and, in addition, to fill enough of bore 14 to bring the upper level of the gel body immediately below and adjacent 20 perforations 19. There is then introduced above the gel body 12 a charge of plugging agent 13 and pressure is applied to drive the plugging agent through perforations 19 and into water bearing stratum 15. When the plugging action 25 is complete, the gel body is removed by bailing or pumping.

The invention is also applicable to drilling operations when, during drilling, a water stratum is passed and the flow from this stratum is not prevented or counteracted by the hydrostatic pressure of the drilling mud column. This condition is not always recognized until the bore has progressed considerably beyond the water-bearing stratum. Often, such water is highly corrosive 35 and therefore damaging to the drill pipe. Also, when entering the bore in large quantities, water makes it impossible to keep the drilling mud of proper consistency.

In such instances, application of this invention is desirable and advantageous in conserving plugging agent and in preventing application of plugging agents to portions of the bore not desired to be treated therewith.

What we claim is:—

1. A method of selectively sealing or solidifying water-bearing strata by impregnation in wells penetrating such strata and also penetrating lower, oil-bearing strata, which comprises establishing in the well a body of gel extending 50 up adjacent but below the water strata and closing off the oil strata, injecting a liquid sealing agent into the well above the gel body and forcing the sealing agent into the water-bearing strata to impregnate said strata and seal them, the sealing agent being prevented from entering the oil strata by the gel body, and then removing the gel body, leaving the oil strata exposed.

2. The method of claim 1 wherein the body of gel is aqueous bentonite gel.

3. The method of claim 1 wherein the sealing agent is silicon tetrachlorid in liquid condition.

4. The method of claim 1 wherein the sealing agent is a solution of rosin size.

5. A method of sealing a water-bearing formation in wells having a casing perforate adjacent the water-bearing formation and through which water leaks into the well, which comprises establishing in the well a body of gel extending up to adjacent but below the perforate portion of 70 the casing, injecting a liquid sealing agent into the well above the gel body and forcing the sealing agent through the perforations into the adjoining formation to prevent further leakage of water into the well.

6. A method of selectively sealing or solidifying water-containing strata in wells, the water-containing strata occurring at a level above the bottom of the well, which comprises establishing in the well a body of gel extending from the bottom of the well up adjacent but below the water-containing strata, and injecting a liquid

5 sealing agent under high pressure into the water bearing strata to impregnate said strata and seal them, the sealing agent being localized at the water-containing strata through the agency of the gel body.
